UNITED STATES PATENT OFFICE.

ALFRED F. MEYER, OF MORTON, ILLINOIS, ASSIGNOR TO MORTON CORPORATION, OF MORTON, ILLINOIS, A CORPORATION OF ILLINOIS.

ELEVATOR.

1,395,986.

Specification of Letters Patent.

Patented Nov. 1, 1921.

Application filed December 14, 1917, Serial No. 207,047. Renewed March 31, 1921. Serial No. 457,421.

To all whom it may concern:

Be it known that I, ALFRED F. MEYER, a citizen of the United States, residing at Morton, in the county of Tazewell and State of Illinois, have invented certain new and useful Improvements in Elevators, and do hereby declare that the following is a full, clear, and exact description of the invention, which will enable others skilled in the art to which it appertains to make and use the same.

This invention relates to improvements in elevators, particularly that class used in granaries and like places where grain, especially ear corn, is to be conveyed from one receptacle to another.

It still further relates to improvements in elevators of the permanently located so called "vertical" type used for elevating grain.

20 The main object of the invention is to construct an elevator and boot wherein the elevating chain is guided through a runway upon an abutment in such boot in lieu of the usual sprocket wheel or wheels so that the entire space in the boot will be devoid of obstructions such as usually interfere with the handling of materials, especially ear corn.

Another object is to provide a structure in an elevator boot by which the elevating chain does not require the sprocket wheels and their supporting shafts ordinarily used in said boot so that the elevating buckets therefor carrying the ear corn can travel freely with no danger of damaging them or of breaking the chain or straining any of the portions of the elevator structure with the added advantage of requiring less power for the elevating operation.

40 Another object is to furnish an elevator boot structure in which, together with the fact that said boot is free and open for substantially its entire area at one side for receiving the ear corn, a larger bulk of the latter can be accommodated resulting in a saving of time required in elevating a given quantity thereof.

Still another object is to provide an elevator structure wherein the elevating chain in its boot is adapted to operate the usual drag chain of the conveyer that supplied grain to such boot.

50 Other objects and advantages will appear as the description proceeds, the invention relating also to certain details of construction

and arrangement of parts to be pointed out herein and form the subject of certain of the claims.

In order that the invention may be clearly understood, I have provided the accompanying drawings showing a preferred manner of constructing the elevator and its boot, though it is to be understood that changes may be made such as will still lie within the meaning and intent of the invention and the scope of the claims.

65 Figure 1 is an elevation of a granary showing my improved elevating structure therein.

70 Fig. 2 is a sectional elevation of a part of the leg of the elevator.

75 Fig. 2^a shows, in perspective, certain details of construction of the elevator boot.

Fig. 3 shows, in perspective, portions of the structure illustrated in Fig. 2.

Fig. 4 is a sectional elevation of the elevator boot.

Fig. 4^a is a detail of a portion of the elevating chain.

Fig. 4^b is a detail, in perspective, of a portion of one of the sides of the elevator boot; and,

Fig. 5 is a horizontal section of the elevator boot showing a loading conveyer associated therewith.

85 A indicates, as a whole, the leg of the elevator, and B the boot thereof. For convenience in constructing the latter portion two parallel side members C are employed, which may be castings, each of which includes an outwardly extending annular portion D 90 forming inner channels E, opposite inner surfaces of which constitute abutments, each channel receiving an elevating chain made up of pairs of connected links F and rollers H.

95 J indicates a sheet iron member stationed between the spaced members C, there being a flange K on the inner face of each of the latter, for example, to receive the member J against it, bolts L serving to clamp the sides and said member together to form a rigid structure.

100 The said side members C are each provided with an outwardly extending flange portion M, Fig. 4^b forming a support for 105 timbers N, N, O spaced from one another as clearly shown in Fig. 4, providing guideways P communicating with the said chan-

nels E, the sheet iron member J extending up upon the outer surface of said timbers N to complete the leg.

One of the members C entirely closes the boot at one side as Q, Figs. 4 and 5, while the opposite member is furnished with a very large receiving opening R for the grain.

S indicates the usual conveyer or drag, 10 and T is a chute to receive the grain therefrom and conduct it into the boot.

U, Figs. 4 and 5, indicates a stud extending from one of the side members C to support the conveyer and upon which said conveyer may swing vertically, although it is to be understood that other means of supporting said conveyer may be provided.

V, Fig. 4, is a sprocket wheel secured upon a sleeve W rotatably mounted upon the stud, 20 which structure is well understood, the usual sprockets 2 of the conveyer being secured to said sleeve. 3 indicates the drag chains for the conveyer and 4 the flights secured thereto. 5 is a shaft mounted in suitable 25 bearings 6 secured to the sides of said boot. At one end of the said shaft is secured a sprocket wheel 7 over which is trained a sprocket chain 8 also trained over the mentioned sprocket V of the conveyer.

30 The opposite end of the shaft 5 is furnished with a sprocket wheel 9 which at one edge projects through a slot 10, Figs. 2^a and 5, in the boot and leg structure into one of the channels E and in the path of travel of 35 the chain F, H which is provided with the usual elevating buckets 11 which have been shown in broken lines in the figures.

The right hand stretch of the chain as viewed in Fig. 4 travels downward to work 40 into and pick up the grain and as the sprocket wheel 9 engages this portion of the chain it is rotated contrary clockwise as viewed in said Fig. 4, with the result that 45 the flights 4 of the conveyer or drag will travel in the proper direction to discharge the material into the chute T, the chain F, H being driven by any suitable power attached at any point.

The diameter of the boot structure is 50 much greater than the width of the leg A in order that, first, the chain in traveling through the long curved track furnished by the channels E may have free movement by disposing the links so as to have as nearly 55 a straight pull as possible, and, second, in order to provide a very large receiving space for the grain. The leg A can be made comparatively small in compass so as to reduce its cost and the space required for it.

60 Another advantage in making the boot much greater in diameter than the measurement of the leg A is that the ascending chain portion is bent inwardly as it moves along the abutments which create the channels E 65 and thus any ears that are in excess of those

required to completely fill the buckets will slide off into the boot due to the inclination of said buckets but should any of them be still retained their disposal will be as explained later.

The leg is slightly wider than the space required for the buckets 11 as they pass one another, and, as shown in Fig. 2, a dividing member 12 is employed which lies nearest the descending line of buckets, thus giving 75 greater space to the ascending line.

The purpose of this peculiar disposal of the dividing member is that when the chain is ascending at an angle such as shown in Figs. 1 and 2 any ears that fall from the 80 buckets will have room to pass between the buckets and the member 12 without becoming wedged and the latter will guide the ears back into the boot or into one of the ascending buckets lower down, said member 85 serving as a chute for the purpose.

In Figs. 1, 2 and 3 I have shown a structure which provides for slight changes in the angle of the upper portion of the elevator leg as occasion may require.

90 There is provided a pair of castings 13, but one of which is shown, each having a face to lie flush with the inner surfaces of the timbers N, N, O, there being channels 13' for the chains, there also being flange portions 14 to receive the said timbers. These flange portions have extended cheek-portions 15 which are received into the timbers by slightly recessing the latter as shown at 16.

95 This casting may be used for a number of 100 different angles at which it may be desired to place the timbers of the upper end of the leg. This may be accomplished by simply changing the angle at which the timbers may be cut at their lower ends where they 105 rest upon the casting. The differences in inclination of the timbers has been indicated by the two series of dotted lines in Fig. 3.

The described member 12 of Fig. 2 is 110 preferably of sheet iron and is secured to a flange 17 on each of the described castings 13 and to strips 18 on the timbers.

115 It is clear that any slight changes in the angle of the upper portion of the leg will not effect the free running of the elevating chain since the channels 13' provided in the castings will smoothly guide the rollers H.

In boot structures it has been customary to provide certain internal structures to prevent the ear corn catching upon the sprocket 120 wheels, shafts or other parts of the structure for preventing breakage of the chain, or parts as stated earlier herein. This makes for complications and even then the danger to the parts is not entirely eliminated and in 125 view of this the herein described structure is provided whereby there are no parts in the way of the buckets 11 but, instead, there is an entirely clear space for the reception of the material to be elevated and for the 13

buckets which, even after passing into the leg, are in no danger of being caught by any part nor is there danger of wedging of the ears between the buckets and other parts.

5 The elimination of the usual sprocket or other wheels in the boot for the purpose of carrying the chain necessitates the channels E in my structure and in order to provide for a free travel of the chain the rollers H 10 are provided. While the use of rollers upon a chain is old it is believed to be new to employ a chain within a channel in a boot substantially as shown and described, the rollers being naturally used to reduce the friction.

15 Having thus described my invention, I claim:—

1. An elevator boot including in its construction an abutment at each of two of its facing sides, a flexible member arranged to 20 travel upon each of the same including elevating devices common to both, one of said sides having an unobstructed opening therein inward from the abutment of said side, the interior of the boot being entirely unob- 25 structed.

2. An elevator boot including in its construction a curved abutment on the inner face of each of two of its opposite sides forming tracks, a flexible member arranged 30 to travel upon each including elevating devices common to both, one of said sides having an unobstructed opening therein communicating with the interior of the boot inward from the abutment of said side for the introduction of materials to be elevated, the 35 interior of the boot being entirely unobstructed except for said elevating devices.

3. An elevator boot including in its construction a substantially cylindrically curved 40 abutment on the inner face of each of two opposite sides thereof each forming a track and each terminating in spaced extensions at the upper side of the boot, a flexible member to run upon each, elevating devices extending between and carried by the members, being the only obstructing portions in 45 said boot, one of the said sides having an unobstructed opening inward from the abutment between the extensions thereof communicating with the interior of the boot for the introduction of material to be elevated.

4. A structure for handling loose material including a boot having spaced substantially cylindrically curved abutments on the 50 inner face of each of two facing sides terminating in spaced extensions, said boot being devoid of interior obstructions, a flexible member adapted to travel in each guideway formed by said spaced abutments, and a receiving opening in one of said sides spaced inward from the guideway at that side communicating with the interior of the boot.

5. A boot for an elevator including in its construction an abutment forming a guide 55 at each of two sides thereof lying opposite

one another and substantially annular in form and each having terminal ends at the upper portion of said boot, the said upper portion of the boot having openings outward from said terminal ends, and a chain 70 arranged to travel upon and around each abutment through said openings, including elevating devices, one of said sides of the boot having a receiving opening lying substantially at the center from which the abutment is described and wholly unobstructed, the boot being otherwise imperforate, its interior being wholly unobstructed inward 75 from the path of travel of the elevating devices.

6. A grain elevating structure including a leg and boot, the leg having spaced guideways extending longitudinally thereof in two opposite sides, said boot having in each of two opposite walls spaced abutments 80 creating a channel of annular form communicating with each guideway forming a continuous runway, and an elevating device received into each of the channels guided by and adapted to travel upon the shortest 85 walls including buckets connected between the devices extending laterally beyond the path of the latter in each direction, one of said walls having an unobstructed opening therein inward from the path of travel of 90 the ascending and descending buckets, the boot and leg being otherwise imperforate, and being wholly unobstructed interiorly.

7. In combination, an elevator leg and boot, a flexible elevating member running 100 through the same, an abutment constituting a guide for said member, a conveyer arranged for discharging materials into said boot including a drag-member therein, and mechanism to operate said drag-member 105 comprising a rotatable member engaging said elevating member, the latter being held operatively in positive engagement with the rotatable member by said guide.

8. An elevator leg and its boot, the latter 110 including an abutment forming an annular guideway, a material moving member disposed in said guideway, a conveyer for discharging material into said boot including a drag, and mechanism to operate said drag 115 including a wheel mounted on said boot extending into said guideway and having engagement with the material moving member, the walls of the guideway adapted to hold the member in positive operative engagement with the wheel.

9. In combination, an elevator leg and its boot having an abutment creating a guideway in each of two opposite walls, an elevating chain disposed in each guideway, a conveyer including a drag member pivotally mounted at one end alongside the boot adapted to tilt upward on its pivot, the boot having an opening in one of its sides, a receiving chute for said boot at 130

said opening receiving material from the conveyer, and a sprocket wheel engaging the chain arranged to drive the drag member, the wall of the guideway holding the 5 chain in positive engagement with the said sprocket wheel.

10. An elevator boot comprising in its construction a pair of spaced side members, each including spaced abutments creating 10 a groove in each said member, part thereof being of an annular form, each groove communicating with the space between said members within said boot and converging at the top portion of said boot parts thereof 15 lying substantially parallel to one another at said top portion, there being a receiving opening in one of the side members lying inward from the groove in that member.

11. An article of manufacture comprising 20 two spaced side members, and a wall extending between the same forming together with said members a container open at one side, the said side members each having spaced annular abutments forming channels at its 25 inner surface terminating in open ends in the edges of said members at said open side of said container, the channels being substantially the same width throughout.

12. An article of manufacture comprising 30 two spaced side members, and a wall extending between the same, the whole forming a container open at one side, the said side members each having abutments forming an annular groove in its inner surface terminating in open ends, said open ends of each 35 groove being spaced from one another, the distance between the ends of each being less than the greatest measurement between the said grooves.

40 13. An elevator boot including in its construction a pair of spaced members each abutment forming a guide way in its inner surface, a flexible member disposed in each guideway, material engaging member secured to and between said flexible members, 45 the guideways describing parts of a circle having terminal ends approaching one another and opening through one of the edges of the members whereby the material engaging members are tipped during their 50 movement through said groove.

14. An elevator leg including in its construction two portions disposed at an angle to and communicating with one another, 55 an elevating chain having an ascending and a descending stretch adapted to travel through both portions, and a dividing partition extending from one of said portions into the other and lying nearest the descending stretch of said chain.

60 15. An elevator structure including two portions disposed at an angle to and communicating with one another, an elevating chain having an ascending and a descending 65 stretch arranged for travel therethrough,

and a dividing partition extending from one of said portions into the other and spaced widely from the ascending stretch of said chain and lying close to the descending stretch thereof.

70

16. In an elevator structure two portions lying at an angle to and communicating with one another, each comprising spaced members providing pairs of guideways for material-moving-members, and a casting connecting the two portions of the structure, the same having guideways therein in register at their ends with the said guideways between the said spaced members.

75

17. An elevator leg structure comprising two communicating portions disposed at an angle to one another, one resting upon the other, one of them including a boot for receiving material to be elevated, a chain extending through both portions for elevating material from said boot and a dividing partition in one of the portions widely spaced from the ascending stretch of said chain.

80

18. An elevator structure including a portion, two of whose opposite sides are made up of spaced members forming guideways between them extending longitudinally of the structure, a member secured to one end of the portion including grooves communicating with the said guideways, and a second portion likewise comprising spaced members forming guideways between them secured to said member with said guideways in communication with the grooves thereof.

85

19. An elevator structure including two 100 portions the sides of which are each made up of members spaced from one another to create a runway for an elevating member, a casting secured between and to each of the sides of both of said portions and each having 105 a surface substantially flush with the inner surfaces of said sides and having flanges upon which the ends of the members of said portions abut, said castings having grooves in their described surfaces communicating 110 with and connecting the said runways.

105

20. In a grain elevator, in combination, a receiving boot for the grain and a leg including a head, said boot having abutments creating a channel annular in form at each 115 of two sides lying opposite one another, the channels being of a substantially fixed width throughout, one of the sides of the boot having a grain receiving opening inward from the channel thereof, said leg having guideways extending up through its sides opening at their ends into said channels, and a chain disposed within each channel and the guideways including elevating devices.

115

120 21. In a grain elevator, in combination, a receiving boot for the grain and a leg including a head, said boot having abutments creating a channel annular in form at each 125 of two sides lying opposite one another, the

125

130

channels being of a substantially fixed width throughout, one of the sides of the boot having a grain receiving opening inward from the channel thereof, said leg 5 having guideways extending up through its sides opening at their ends into said channels, a chain disposed within each channel and the guideways including elevating devices, and a dividing partition within a 10 part of the leg spaced widely from the ascending stretch of the chain and lying nearest the descending stretch.

22. In a grain elevator, including in combination, a receiving boot for the grain and 15 a leg therefor, said boot having abutments at each of two sides thereof creating a channel partially annular in form in each said side communicating with the interior of

said boot, there being a receiving opening in one of the sides inward from the groove 20 of that side, said grooves each near the top of the boot leaving the annular form thereof and extending into spaced substantially parallel runs, the distance between the runs being less than the diameter of the annular 25 portion, there being two parallel grooves in corresponding sides of the leg communicating with the extensions of the groove at said runs.

In testimony whereof I affix my signature in presence of two witnesses.

ALFRED F. MEYER.
